UNITED STATES PATENT OFFICE.

ANTONE FREITAS, OF LAHAINA, MAUI, TERRITORY OF HAWAII.

PROJECTILE.

1,373,322.

Specification of Letters Patent. Patented Mar. 29, 1921.

Application filed January 10, 1919. Serial No. 270,527.

To all whom it may concern:

Be it known that I, ANTONE FREITAS, a citizen of the United States, residing at Lahaina, on the Island of Maui, Territory 5 of Hawaii, have invented new and useful Improvements in Projectiles, of which the following is a specification.

The purpose of the invention is to provide a new and novel form of projectile 10 with which there is associated a peculiar form of nose that is designed to give the projectile its rotary movement when being fired, the peculiar shaped nose serving to keep the projectile positioned always nose 15 forward.

To the exact construction in which it is shown and described the invention is not to be restricted. The right is reserved to make such changes or alterations as the 20 actual reduction to practice may suggest, in so far as such changes or alterations are compatible in spirit with the annexed claim.

In the accompanying drawings:

Figure 1 is a view in side elevation of 25 the improved projectile.

Fig. 2 is an end elevation looking at the nose of the device.

Fig. 3 is a section on the line 3—3 of Fig. 1.

As shown in the drawings, the projectile 30 comprises a cylindrical body 1 at substantially the longitudinal center of which the flutes 2 begin, the latter extending to the forward end of the device and gradually 35 increasing in depth besides being spirally arranged around the body at uniformly spaced angular distances.

The formation of the flutes 2 results in

the provision of the wings 3 which in cross section are of substantially arcuate shape 40 with the curved portions so disposed that they will wipe against the wind when the projectile is rotated, as it is designed to be when fired.

In the operation of the invention it is intended to be fired from a gun whose rifling is intended to create the necessary swirl as the projectile leaves the barrel. Thus as the device leaves the barrel the spirals formed on the nose portion serve to work 50 their way through the air and because of their tapering depth and spiral shape aid in a measure in propelling the projectile aside from offsetting any tendency of the same to assume any position other than that 55 in which the extremity of the nose is foremost.

From the foregoing description and the accompanying drawings, it is believed that a clear enough understanding of the invention is to be had to render a further description unnecessary.

The invention having been described what is claimed as new and useful is:

A device of the kind described comprising a body having spiral flutes formed therein beginning at a substantially intermediate point and continuing to one extremity and gradually increasing in depth from the point of beginning to said extremity, the upper walls of the flutes forming arcuate wings for wiping action against the wind when the device is rotated when fired.

In testimony whereof I affix my signature.

ANTONE FREITAS.
